United States Patent Office

Des. 212,612
Patented Nov. 5, 1963

212,612

FIRE HOSE NOZZLE

Duncan Horatio Campbell, Islington, Ontario, Canada,
assignor to Wilson & Cousins Co., Limited, Toronto,
Ontario, Canada, a company of Ontario, Canada

Filed Aug. 3, 1967, Ser. No. 8,112

Term of patent 14 years

(Cl. D23—34)

FIG. 1

FIG. 2

FIGURE 1 is a perspective view of a nozzle;
 FIGURE 2 is a plane view of the nozzle;
 FIGURE 3 is an exploded perspective view of the first
 and second members of the nozzle.

The dominant features of my design reside in the por-
 tions shown in full lines.

I claim:

The ornamental design for a fire hose nozzle, as shown
 and described.
